(57) **CLAIM**

The ornamental design for a cutting wheel for electric can opener, as shown and described.

DESCRIPTION

FIG. 1 is a first perspective view of a cutting wheel for electric can opener showing the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a second perspective view thereof; and,

FIG. 9 is an enlarged elevational view of a representative corner of the electric can opener.

The broken lines in the figures show portions of the cutting wheel for electric can opener that form no part of the claimed design.
